PLOW FOR LEVELING BALLAST OF
RAILWAY TRACKS

George W. Dangerfield, Mount Holly, S. C.

Application July 22, 1949, Serial No. 106,302

1 Claim. (Cl. 37—104)

This invention relates to a ballast plow for use in spreading and leveling ballast in the construction and repair of railway tracks, the primary object of the invention being to provide a device of this character which will be light in weight to permit handling with facility, the construction of the plow being such as to permit of its attachment to a railway car in such a way that the plow will be held to its work by the weight of the car, to which the plow is attached, thereby eliminating the necessity of using securing brackets, bolts or the like, common in ballast plow construction.

Another object of the invention is to provide a vertically adjustable blade whereby the spreading of the ballast to the desired depth, may be accomplished.

Still another object of the invention is to provide shoes mounted on the plow, against which the wheels of the car with which the plow is used, engage in forcing the plow over the ballast being distributed.

A still further object of the invention is to provide a ballast plow including a rectangular frame with shoes secured along the lower edges thereof, the shoes resting on the rails of the railway track in such a way as to prevent lateral movement of the plow with respect to the track, during its operation.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

Referring to the drawing

Figure 1 is a front elevational view of a ballast plow, constructed in accordance with the invention, portions of the blade supporting member being broken away illustrating the supporting frame of the plow.

Fig. 2 is a plan view of the plow.

Fig. 3 is an enlarged fragmental perspective view illustrating one end of the plow blade.

Fig. 4 is an end elevational view of the plow.

Fig. 5 is a perspective view of a portion of the plow blade and frame, at one end of the plow.

Fig. 6 is a perspective view illustrating the connection between the vertically adjustable truck engaging bar of the frame of the device with the frame.

Referring to the drawings in detail, the plow embodies a rectangular frame including the upper

angle bar 5 and lower angle bar 6 which are held in vertical spaced relation with respect to each other by means of the vertical end bars 7 which have portions of one of the sides thereof cut away adjacent to the ends, so that they fit against the edges of the bars 5 and 6, where they are welded, securing the bars together.

Welded to the bars 5 and 6, and extending rearwardly therefrom in vertical spaced relation with respect to each other, are the side bars 8 and 9 respectively which bars 8 and 9 are connected at their rear ends by means of the curved shoes 10 in which the treads of the car wheels move, the car wheels being indicated by the reference character A, in Fig. 4 of the drawings.

These curved shoes 10 have portions thereof extended forwardly as at 11, where they connect with the side bars 8 and 9 securely bracing the shoes. Further angular braces 12 connect with the bars 9 and forward edges of the curved shoes 10, providing a still further brace for the curved shoes.

Disposed intermediately of the frame, are vertical brace bars 13.

Arranged intermediate the ends of the bars 5 and 6, is a vertical brace bar 14 that is welded thereto, bracing the central forward portion of the frame.

Adjustably mounted for vertical movement on the bars 8, are the short bars 15, which are formed with elongated openings 16 in which the bolts 17 operate, which bolts provide for vertical adjustment of the short bars 15. One flange of each short bar is formed with an elongated opening 18 in which bolts 19 are disposed, the bolts 19 passing through openings in the vertically adjustable clamping bar 20, and are secured to the short bars 15, by means of the nuts 20'.

The frame is also braced by means of the brace bars 21 which have their ends connected with the side bars 8, the brace bars being disposed at oblique angles with respect to the side edges of the bars 8, crossing each other at points intermediate their ends, the ends of the brace bars 21 being welded to the bars 8.

The plow blade is indicated by the reference character 22 and is substantially wide, so that the upper edge thereof extends above the top of the supporting frame. The upper edge of the plow blade 22 is provided with a cut out portion 23 of a width to accommodate the usual coupling bar of a car coupler. Thus when the device is positioned under a car, the coupler bar of the car not shown, will fit therein, holding the device in position.

As clearly shown by Fig. 1 of the drawings, the plow blade 22 is formed with rail notches 23 that are so arranged that they fit over the rails of the track over which the device is moved.

Mounted on the plow blade 22, is an adjustable blade section 24 which is formed with a plurality of elongated openings 25 arranged in transverse spaced relation with respect to each other, the openings aligning with openings in the blade proper 22, for the reception of the securing bolts 26 that secure the blade section 24 to the blade proper 22. Thus it will be seen that due to this construction, the blade section 24 may be adjusted vertically for regulating the depth of operation of the blade 24.

This blade section 24 is also formed with rail notches 27, which notches are considerably larger than the notches 23 formed in the blade proper 22, so that the adjustable blade section 24 may be moved vertically with its lower ballast engaging edge operating at a point an appreciable distance below the tread of the rail.

Secured along the lower front edge of the adjustable blade section 24, is the wear bar 28, the lower front edge of the adjustable blade section 24 being extended outwardly as at 29 to the end that the wear bar 28 will be disposed an appreciable distance in advance of the main portion of the adjustable blade section.

Secured along the lower surfaces of the side bars 9, by means of the bolts 30, are shoes 31, which shoes are formed with flanges 32 that fit over the edges of the rails of a track, holding the frame in true running position over the rails. Since these shoes 31 are of lengths equal to the lengths of the side bars 9, it will be seen that the frame of the plow is supported against twisting under severe strains directed thereto, during the operation of the plow.

In the use of the device, the plow is lifted onto the rails of a railway track in front of the front wheels of a car, the front wheels of the car moving into position on the curved shoes 10. With the plow in this position, the bar 20 is adjusted to engage the under frame work of the car to secure the plow against vertical movement when in use. When the plow has been properly positioned, the usual coupling bar of the car, not shown, will rest in the cut out portion 23

which further secures the plow in position without the use of tie rods, securing bolts, or brackets.

It will also be noted that due to this construction, the plow may be readily and easily handled and therefore placed into and out of operation with facility.

With the plow properly positioned, the plow may be moved over ballast of a railway track construction, spreading and leveling the ballast to the desired degree.

Having thus described the invention, what is claimed is:

A railway ballast plow comprising a frame, a main plow blade extending transversely of the front of the frame, upper and lower side members forming a part of the frame, elongated curved shoes secured to the rear ends of the side members and against which wheels of a railway car engage in moving the frame over a railway track, said plow blade having railway rail notches formed in the lower edge thereof fitted over the rails of a railway track on which the plow is positioned, elongated supporting shoes secured to the bottoms of the lower side members of the frame and extending throughout the length of the frame, with the front ends of said elongated supporting shoes aligning with the said notches, said supporting shoes having rail engaging flanges formed along the inner longitudinal edges thereof, said flanges resting against the inner edges of rails, holding the frame against twisting, and a vertically adjustable plow blade secured to the main plow blade, said adjustable plow blade also having notches registering with the notches of the main plow blade.

GEORGE W. DANGERFIELD.
